UNITED STATES PATENT OFFICE.

WILLIAM H. SAUVAGE, OF NEW YORK, N. Y.

SLACK-ADJUSTER FOR RAILWAY-BRAKES.

1,020,519.

Specification of Letters Patent. Patented Mar. 19, 1912.

Application filed December 27, 1910. Serial No. 599,512.

To all whom it may concern:

Be it known that I, WILLIAM H. SAUVAGE, a citizen of the United States, residing at New York, in the county of New York and State of New York, have invented certain new and useful Improvements in Slack-Adjusters for Railway-Brakes, of which the following is a full, clear, and exact description, such as will enable others skilled in the art to which it appertains to make and use the same.

This invention relates to slack adjusters for the brake rigging of railway cars, and more particularly to a self-contained apparatus which will be automatic in its operation.

One of the objects of the present invention is to provide a simple and practical slack adjuster of the above character.

Another object is to provide an apparatus of the above style which will be cheap to manufacture.

A further object is to provide an automatic slack adjuster that will be positive in its action, reliable in operation and equal in every way to the demands placed thereupon by varying conditions of use.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawing, wherein is shown one of various possible embodiments of this invention, Figure 1 is a side elevation showing the device, partly in section, applied to an ordinary two-wheeled truck, certain parts of the truck being omitted for the sake of clearness; Figs. 2, 3 and 4 are detail views of various parts, as will be more fully hereinafter explained.

Similar reference characters refer to similar parts throughout the several views of the drawing.

While the present invention is shown and described as applied to the central part of the truck between the wheels at opposite sides thereof out of the path of water and snow thrown by the revolving wheels in wet weather, it is, of course, to be understood that it may be applied to beamless trucks at

each side if so desired, or to outside hung brake shoes, without departing from the scope of the invention.

Referring to Fig. 1 of the drawing, in detail, 1 represents the transom of a two-wheeled truck of any well-known make, suspended from which are hangers 2 and 3, supporting the brake beams 4 and 5, respectively, having heads thereon carrying brake-shoes 6 and 7 adapted to coact with the tread of wheels 8 and 9. The break beams 4 and 5 are adapted to be actuated by the relative movement of the live and dead levers 10 and 11, respectively. The live lever 10 is pivotally connected at the upper part thereof with a rod 12 which in turn is connected to the brake rigging mechanism, not herein shown, in such a manner as to be drawn to the left, when air is admitted to the air brake cylinder. Hand brake mechanism may also be connected to the rod 12 when the device is applied to freight cars, for example, to actuate the brake mechanism in a similar manner. The lower ends of the live and dead levers are connected by means of an automatically extensible or two-part telescopic push bar, the effective length of which is changed as the slack is taken up. This bar comprises a rod 13 extending into a hollow casting or barrel-shaped member 14, provided intermediate its ends with an enlarged chamber 15 into which the end of the rod 13 extends. This chamber is rectangular in shape, and is adapted to contain a plurality of relatively small solid objects or shims 16, as shown in detail in Fig. 2. These shims which loosely fit between and interfit with the side walls of the chamber 15 may be considered as being of U-shaped formation, having squared corners to prevent rotation thereof about the rod 13 upon which the shims rest in inverted position. It will thus be seen that as the parts of the push bar are separated and the rod 13 moves out of the chamber 15, the shims 16 will drop down, as shown in the drawings, thereby making a solid continuation of the push bar between the effective ends of the telescoping parts and positively hold the slack taken up. By providing a positive take-up of this character as distinguished from the pawl and ratchet mechanism or a threaded turnbuckle, it will be seen that the danger of stripping the teeth or threads of such mechanisms is avoided, for it frequently happens

that the brakes are suddenly applied in emergency by the operator which temporarily places the maximum strain upon mechanisms of this kind at times, producing disastrous results.

The barrel member 14 which is cored out to a slightly larger diameter than the bar 13, as shown, to prevent friction, is of watertight construction and is provided with a 10 packing ring or gasket 17 at the end thereof surrounding the bar 13 to prevent water from seeping into the chamber and freezing, thereby restricting the free operation of the shims interfitting with the bar 13. A 15 removable cover 18 having a watertight packing ring 19 is provided for the chamber 15 permitting access thereto for replacing or removing shims, for example. At this point it may be noted that the end of the rod 13 20 is slightly beveled, as at 20, whereby the shims extending partially about the bar 13 will more readily drop into place.

Parallel to the push bar, and slightly above the same, is an adjusting rod 21 having one 25 end clamped in a bracket 22 pivotally connected at 23 with the live lever 10. The opposite end of the rod 21 passes through a friction clamp mounted on the dead lever 11. This friction clamp comprises a bracket 24 30 provided with an enlarged and elongated opening 25 at the upper part thereof through which passes a pivot pin 26 for securing the same to the dead lever 11. The slight difference in size between the hole 25 and the 35 pivot pin 26, which in practice is preferably about one-quarter of an inch, is provided for permitting the predetermined slack or lost motion of about one-eighth of an inch between each brake shoe and its adjacent 40 wheel. By providing for a predetermined amount of slack between the brake shoe and the wheel of substantially the amount above set forth, as permitted by the lost motion connection just referred to, the brake shoes 45 are kept out of contact with the tread of the wheels, thereby avoiding any unnecessary wear and friction between the surfaces. There is, however, sufficient friction due to the air passing between the brake shoe and 50 the tread of the wheel as the wheel rotates to prevent moisture from collecting and freezing on the surface of the shoe, as might occur in cold wet weather. This bracket 24 is provided with a longitudinal recess 27 55 (see Fig. 4) which is curved at the rear as shown, to fit rod 21 lying therein. Projecting ears 29 are provided near each end of this recess through which pass pins 30 to hold a flat resilient spring member 31 and 60 wear plate 28 in contact with the rod 21. The ends of the plate 28 are adapted to remove dirt or ice from the rod 21 that would otherwise form between the spring and rod. This form of friction contact or friction 65 clamp permits the rod 21 to move relatively

to the bracket 24 in either direction, as may be required under different conditions.

Mounted upon the rod 21 at the left of the friction clamp is an adjustable collar 32 forming an abutment for one end of a coiled spring 33 about the rod 21. Rigidly secured upon the bar 13 is a yoke 34 (see Fig. 3) having an elongated slot 35 in the upper part thereof through which passes the rod 21, and forming an abutment for the opposite end of the coiled spring 33. This spring, which forms an integral part of the adjuster, not only acts as a means for extending or spacing the parts of the push bar, but also returns the brake shoes and other parts to normal position. The normal tension of this spring holds the mechanism in position to become immediately operative when the brake system is actuated without waiting to take up the several little lost motions due to 75 wear, as might occur at the various pivotal connections. In other words, the play which may occur between the pivot pins and the connected parts is automatically taken up by this spring at all times, except the intended lost motion between the slot and pin connection 25 and 26.

The entire apparatus, while designed to be automatic in its operation, is so constructed as to be manually adjusted in its 95 initial application to a truck, or for example, when one or both wheels are replaced by or turned down to wheels of a smaller diameter. The first adjustment comprises a member 36 secured to a relatively fixed part of the truck 100 and having a plurality of holes 37 adapted to be engaged by a pin 38 pivotally connecting the dead lever 11 thereto. Likewise the stirruped end of the casting or barrel-shaped member 14 is provided with holes 39 to 105 either one of which the lower end of the dead lever may be connected by a pivot pin 40, depending upon the size of the wheel 9 to which the brake is to be applied.

It is thought that the operation or method of using this apparatus should be clear from the description hereinabove set forth, but a brief statement thereof is as follows: When the brakes are applied, the live lever 10 moves toward the left under the action 115 of the air or hand brake levers and connection 12. This lever will first use the end of the bar 13 or pivotal connection 41 as a fulcrum and move the adjusting rod 21 to the left therewith, thereby to take up the predetermined slack or lost motion allowed between the hole 25 and pin 26 supporting the rod 21 from the dead lever 11. As above explained, the taking up of this predetermined lost motion is sufficient to carry 125 the brake shoes into contact with the tread of the wheels and apply the brakes. However, as the brake shoes wear down in the course of time it will be necessary for them to travel beyond the distance allowed by the 130

lost motion connection. It is quite clear that any further movement of the lever 10 will cause a relative slipping movement between the rod 21 and the friction clamp 24, thereby to compress the coiled spring 33 more than an amount normally sufficient to return the parts to their original position. This relative movement is taken up and temporarily held by the friction clamp as long as the brakes are in applied position, and when they are released and the live lever 10 starts to return to normal position the friction between the clamp and rod 21 will be sufficient to hold the adjusting rod 15 in its temporarily adjusted position after the predetermined lost motion at the connection 26 has been taken up. The pivotal connection 23 now acts as a fulcrum and the expansion of the spring 33 acting against the yoke 34 forces the end of the bar 13 toward the left, thereby returning the upper end of the live lever 10 to its full normal or release position. This outward movement of the bar 13, or relatively to the barrel member, permits one or more of the shims 16 to drop down in the position shown, thereby making a solid connection between the adjacent effective ends of the telescoping parts and permanently taking up the slack. It is quite clear that such a rigid construction as this will permit the brakes to be applied or released instantaneously, which would not be feasible in a pawl and ratchet construction or turnbuckle take-up, due to the danger of stripping the teeth or threads of the mechanism. It is to be noted that a slack adjuster of this style always maintains the live and dead levers in the same relative position, thereby affording a uniform piston travel in the air brake cylinder.

When the shoes have become so worn down that it is necessary to change the same, it will also be necessary to restore the push bar to its contracted position. This may be conveniently done by removing the pin 40, connecting the dead lever 11 with the member 14, and forcing the brake beam 5 rearwardly sufficient to permit the shoe to be changed. The barrel member 14 is then inverted, which will restore the shims to their original relative position and permit the bar 13 to be moved into the chamber 15. Then, as the member 14 is again turned over, the shims all rest on the bar 13 and the parts are in position to be again connected. The first application of the brakes will automatically adjust the apparatus to its new conditions in substantially the manner above described. It will thus be seen that this invention provides for a simple and practical slack adjuster, accomplishing, among others, all of the objects and advantages above set forth.

As many changes could be made in the

above construction and many apparently widely different embodiments of this invention could be made without departing from the scope thereof, it is intended that all matter contained in the above description or shown in the accompanying drawings shall be interpreted as illustrating and not in a limiting sense. It is also to be understood that the language used in the following claims is intended to cover all of the generic and specific features of the invention herein described, and all statements of the scope of the invention which, as a matter of language, might be said to fall therebetween.

Having described my invention, what I claim as new and desire to secure by Letters Patent is:

1. In an apparatus of the character described, in combination a live lever, a dead lever, a two part push bar connecting said levers, a plurality of shims associated with said bar adapted to drop down between the effective ends thereof as the length of said bar is altered, one of the parts of said push bar being so constructed as to permit its rotation to return the shims to their original relative position from between the effective ends of the parts of said push bar.

2. In an apparatus of the character described, in combination, a live lever, a dead lever, a two-part extensible coupling member therebetween, and shims adapted to be interposed between the effective ends of said parts as the length thereof is changed to take up the slack due to wear of the brake shoes, one of said parts being rotatable relatively to the other whereby the bar may be returned to its original length, and the shims returned to normal position.

3. In an apparatus of the character described, in combination, a live lever, a dead lever, an adjusting bar adapted temporarily to take up the slack due to the wear of the brake shoes, and a two-part push bar connecting said levers adapted permanently to take up said slack, one of the parts of said push bar being rotatable relatively to the other whereby said push bar is restored to its original effective length.

4. In an apparatus of the character described, in combination, a live lever, a dead lever, a two-part push bar connected therewith, a second connection between said levers for temporarily taking up the slack, means connecting said second connection with one of the parts of said push bar whereby the same is actuated permanently to take up the slack, a plurality of shims adapted to be carried on one of the parts of said push bar and adapted to be interposed between the adjacent effective ends permanently to hold the slack taken up, and a water-tight casing inclosing said shims.

5. In an apparatus of the character described, in combination, a live lever, a dead

- lever, a connection therebetween comprising a telescopic push bar, means for changing the position of the parts of said push bar for the purpose of permanently taking up 5 the slack, a plurality of shims adapted to be interposed between the adjacent effective ends of said push bar, and a water-tight shim box inclosing said shims.
6. In an apparatus of the character described, in combination, a live lever, a dead lever, and an automatically extensible connection therebetween comprising a two-part telescopic push bar, one of said parts being enlarged and adapted to form a chamber 10 inclosing a plurality of shims resting upon the other, whereby the shims drop down between the adjacent effective ends as said push bar is extended said chamber having a removable cover whereby the shims may be 20 easily removed therefrom.
7. In an apparatus of the character described, in combination, a live lever, a dead lever, and a telescopic push bar connection therebetween, rigid means adapted to be interposed between the adjacent ends of said 25 push bar as the same is extended, and spring means adapted to act upon one of said parts to extend the push bar as the brakes are released.
- 30 8. In an apparatus of the character described, in combination, a live lever, a dead lever, and a telescopic push bar connection therebetween, rigid means adapted to be interposed between the adjacent effective ends 35 of said push bar as the same is extended, and spring means adapted to return the parts to normal position and act upon one of said parts to extend the push bar as the parts are returned to normal position.
- 40 9. In an apparatus of the character described, in combination, a telescopic push bar comprising two relatively movable parts, one of said parts having an enlarged chamber containing a plurality of U-shaped 45 shims adapted to be interposed between the effective ends of the parts of said push bar as they assume adjusted position.
- 50 10. In an apparatus of the character described, in combination, a telescopic push bar comprising two relatively movable parts, one of said parts having an enlarged chamber containing a plurality of U-shaped shims adapted to be interposed between the effective ends of the parts of said push bar 55 as they assume adjusted position, said U-shaped shims having means to prevent rotation thereof within said chamber.
- 60 11. In an apparatus of the character described, in combination, a telescopic push bar adjustable to change its length permanently to hold the slack taken up thereby comprising two relatively movable parts, and non-rotatable shims adapted to be interposed between the separated ends of said parts.
- 65 12. In an apparatus of the character de- scribed, in combination, a two-part telescopic push bar, the outer of said parts having an enlarged chamber, a water-tight cover permitting access thereto, and a plurality of shims resting upon one of said parts 70 adapted to be interposed between the effective ends of said push bar as its length is changed permanently to hold the slack taken up thereby.
13. In an apparatus of the character described, in combination, a telescopic push bar comprising a cylindrical rod and a barrel-shaped casting within which said rod is movable, a packing ring on said casting near one end thereof surrounding said rod 75 adapted to make a water-tight connection, said casting having an enlarged chamber near the central part thereof containing a plurality of relatively small objects adapted to be interposed between the effective ends 80 of said push bar as its length is altered permanently to hold the slack taken up thereby.
14. In an apparatus of the character described, in combination, a telescopic push bar comprising a cylindrical rod and a barrel-shaped casting within which said rod is movable, and a packing ring on said casting near one end thereof surrounding said rod 90 adapted to make a water-tight connection, said casting having an enlarged chamber containing a plurality of U-shaped shims resting upon said rod and adapted to drop down between the end thereof and the end of the chamber to make a solid connection between said parts permanently to hold the slack taken up thereby.
15. In an apparatus of the character described, in combination, a telescopic push bar comprising a cylindrical rod and a member within which said rod is movable, and a packing ring on said member near one end thereof surrounding said rod adapted to make a water-tight connection, said member having an enlarged chamber containing 105 a plurality of U-shaped shims resting upon said rod and adapted to drop down between the end thereof and the end of the chamber to make a solid connection between said parts permanently to hold the slack taken up thereby.
16. In an apparatus of the character described, in combination, a telescopic push bar comprising a cylindrical rod and a member within which said rod is movable, and a packing ring on said member near one end thereof surrounding said rod adapted to make a water-tight connection, said member having an enlarged chamber containing 115 a plurality of U-shaped shims resting upon said rod and adapted to drop down between the end thereof and the end of the chamber to make a solid connection within said chamber.
17. In an apparatus of the character described, in combination, a telescopic push bar comprising a cylindrical rod and a member within which said rod is movable, and a packing ring on said member near one end thereof surrounding said rod adapted to make a water-tight connection, said member having an enlarged chamber containing 120 a plurality of U-shaped shims resting upon said rod and adapted to drop down between the end thereof and the end of the chamber to make a solid connection.
18. In an apparatus of the character described, in combination, a telescopic push bar comprising a cylindrical rod and a member within which said rod is movable, and a packing ring on said member near one end thereof surrounding said rod adapted to make a water-tight connection, said member having an enlarged chamber containing 125 a plurality of U-shaped shims resting upon said rod and adapted to drop down between the end thereof and the end of the chamber to make a solid connection.

- therebetween, said member being rotatable on said rod to restore said shims to their original position.
17. In an apparatus of the character described, in combination, a telescopic push bar comprising a cylindrical rod and a casting within which said rod is movable, and a packing ring on said casting near one end thereof surrounding said rod adapted to 5 make a water-tight connection, said casting having an enlarged chamber containing a plurality of U-shaped shims resting upon said rod and adapted to drop down between the end thereof and the end of the chamber 10 to make a solid connection between the effective ends of said parts permanently to hold the slack taken up thereby, said chamber having a water-tight cover permitting access to the interior thereof.
18. In an apparatus of the character described, in combination, a telescopic push bar comprising two relatively movable parts, one of said parts having an inclosed rectangular chamber containing a plurality 15 of shims resting upon the other of said parts and loosely fitting between the side walls of said chamber whereby the rotation of said shims about the part upon which they rest is positively prevented.
19. In an apparatus of the character described, in combination, a telescopic push bar, an enlarged chamber associated with one of the parts of said push bar, and shims in said chamber interfitting with the other 20 part of said bar and the wall of said chamber whereby a rotation thereof within said chamber is at all times prevented.
20. In an apparatus of the character described, in combination, a telescopic push bar, an enlarged chamber associated with one of the parts of said push bar, and U-shaped shims within said chamber resting upon and extending partially about the other part of said push bar.
21. In an apparatus of the character described, in combination, a telescopic push bar, an enlarged chamber associated with one of the parts of said push bar, and shims within said chamber extending partially 25 about the other part of said push bar and adapted to interfit with the sides of said chamber whereby rotation thereof within said chamber is positively prevented.
22. In an apparatus of the character described, in combination, a two-part telescopic push bar, one of said parts having an enlarged portion forming a shim chamber into which the other part projects, and a plurality of shims within said chamber 30 adapted to interfit between the parts of said push bar as the same assumes extended position the part of said bar having an enlarged portion being so formed as to permit a rotation thereof whereby the shims may be returned to their original relative position,
- thereby permitting a compression of said push bar.
23. In an apparatus of the character described, in combination, a two-part telescopic push bar, one of said parts having an enlarged portion forming a shim chamber into which the other part projects, and a plurality of shims within said chamber interfitting with the side walls thereof to prevent rotation and extending partially 35 around the other part of said push bar.
24. In an apparatus of the character described, in combination, an extensible push bar, and shims adapted to interfit with the parts of said push bar to prevent a rotation thereof and drop between the effective ends thereof when extended.
25. In an apparatus of the character described, in combination, an extensible push bar, and shims adapted to interfit between the effective ends thereof, said shims being cut to permit their removal upward from the part of the push bar upon which they rest and provided with means whereby relative rotation thereof is positively prevented.
26. In an apparatus of the character described, in combination, an extensible two part push bar, and shims adapted to interfit between the effective ends thereof, said shims being cut to fit the part of the push bar upon which they rest and provided with means adapted to coact with the other part of said push bar whereby a rotation thereof is positively prevented.
27. In an apparatus of the character described, in combination, a two-part telescopic push bar, and spring means directly coacting with one of said parts positively to separate the effective ends of said push bar.
28. In an apparatus of the character described, in combination, a two-part telescopic push bar connecting the live and dead levers of brake rigging, a connection parallel with said push bar, and spring means on said connection directly coacting on one of the parts of said push bar positively to separate the effective ends of said push bar as the brakes are released.
29. In an apparatus of the character described, in combination, a two-part telescopic push bar interposed between the live and dead levers of brake rigging, a rod parallel thereto, a spring upon said rod and reacting on one of the parts of said push bar positively to space the same as the 100 brakes are released, and means adapted to be interposed between the effective ends of said push bar permanently to hold the parts in adjusted position, said means including a plurality of non-rotatable shims and a 105 water-tight chamber inclosing said shims.
30. In an apparatus of the character described, in combination, a live lever, a dead lever, a two-part telescopic push bar interposed between said levers, one part rotatable 110

6 relatively to the other to permit a change in the effective length of said bar, and an adjusting bar connecting said levers, said adjusting bar comprising two relatively 5 movable members having a frictional engagement with each other, and one of said relatively movable members being connected with the adjacent lever whereby a predetermined amount of lost motion is provided 10 said connection.

31. In an apparatus of the character described, in combination, a live lever, a dead lever, a telescopic push bar connecting said levers, an adjusting bar connecting said 15 levers, a release spring, and an abutment on one of said parts and a yoke on the other whereby said spring is compressed between said abutment and yoke as the brakes are applied and reacts to return the parts 20 to normal position and separate said telescopic connection as the brakes are released one of the parts of said push bar being rotatably mounted upon the other whereby the parts may be restored to a position to permit 25 the replacing of the worn brake shoes.

32. In an apparatus of the character described, in combination, a live lever, a dead lever, a bracket having a lost motion connection with one of said levers, a friction 30 clamp carried on said bracket, a rod connected with the other of said levers passing through said friction clamp and movable in both directions therein, means associated with said clamp adapted to remove foreign 35 matter from the rod as it passes therethrough, a telescopic push bar connecting said levers, a spring on said rod, means on said rod and push bar engaging the opposite ends of said spring whereby the same is 40 compressed as the brakes are actuated, said spring adapted to react to return the parts to normal position and separate the parts of said telescopic push bar when the brakes are released, and solid means adapted to be interposed 45 between said parts when separated.

33. In an apparatus of the character described, in combination, a live lever, a dead lever, a friction clamp pivotally connected with one of said levers and affording a predetermined amount of lost motion at the 50 point of connection, a rod pivotally connected with the other lever and operable in both directions through said friction clamp, a wear plate carried by said clamp engaging 55 said rod, a two-part telescopic push bar connecting the lower ends of said live lever and dead lever, an abutment carried on said rod, a yoke carried by one of the parts of said push bar, and a spiral spring on one of said 60 parts and interposed between said yoke and abutment and adapted to be compressed when the brakes are applied to measure the slack exceeding the lost motion and expand as the brakes are released to separate the 65 adjacent parts of said telescopic push bar

when said slack exceeds the predetermined lost motion.

34. In an apparatus of the character described, in combination, a live lever, a dead lever, a friction clamp pivotally connected 70 with one of said levers and affording a predetermined amount of lost motion at the point of connection, a rod pivotally connected with the other lever and operable in both directions through said friction clamp, 75 a two-part telescopic push bar connecting the lower ends of said live lever and dead lever, an abutment carried by said rod, a yoke carried by one of the parts of said push bar, and a spiral spring on said rod 80 interposed between said yoke and abutment and adapted to be compressed when the brakes are applied to measure the slack exceeding the lost motion and expand to separate the adjacent parts of said telescopic 85 push bar when said slack exceeds the predetermined lost motion, one of the parts of said telescopic push bar being enlarged to form a water-tight chamber adapted to 90 inclose a plurality of shims resting upon the other part of said push bar, said shims adapted to be interposed between adjacent effective ends of said push bar permanently to hold the parts in adjusted position.

35. In an apparatus of the character described, in combination, a live lever, a dead lever, a friction clamp pivotally connected with one of said levers comprising a relatively flat spring held plate covering a curved recess, a rod pivotally connected with the other of said levers and adapted to pass through said recess and be gripped by the said plate whereby it is operable in both directions, a telescopic relatively adjustable push bar connecting the lower ends of said live lever and dead lever, an abutment carried on said rod, a yoke carried by one of the parts of said push bar, and a spiral spring interposed between said yoke and abutment 100 adapted to be compressed when the brakes 105 are applied to measure the slack exceeding the lost motion and expand to separate the adjacent parts of said telescopic push bar to accommodate the excess slack.

36. In an apparatus of the character described, in combination, a live lever, a dead lever, a two-part telescopic push bar connecting said levers, one of said parts being enlarged to form a water-tight chamber, and a plurality of U-shaped shims inclosed 110 within said chamber and resting upon the end of the push bar extending into said chamber whereby the same will drop down as the rod is extended to make a solid continuation of the bar and positively hold the 115 slack thus taken up.

37. In an apparatus of the character described, in combination, a live lever, a dead lever, a two-part telescopic push bar connecting said levers, one of said parts being 120

enlarged to form a water-tight chamber, and a plurality of U-shaped shims inclosed within said chamber and resting upon the end of the push bar extending into said chamber whereby the same will drop down as the rod is extended to make a solid continuation of the bar and positively hold the slack thus taken up, the end of said bar extending into said chamber being slightly beveled or rounded to permit the shims easily to drop into place.

38. In an apparatus of the character de-

scribed, in combination, a clamping device having a recess therein, a rod adapted to pass through said recess, a wear plate engaging said rod, and resilient means for holding said wear plate in contact with said rod.

In testimony whereof I affix my signature, in the presence of two witnesses.

WILLIAM H. SAUVAGE.
